UNITED STATES PATENT OFFICE.

FLOYD LANE, OF FALCONER, NEW YORK.

MILK-BOTTLE CAP.

1,265,457.

Specification of Letters Patent.

Patented May 7, 1918.

Application filed March 28, 1917. Serial No. 157,987.

To all whom it may concern:

Be it known that I, FLOYD LANE, a citizen of the United States, residing at Falconer, in the county of Chautauqua and State of New York, have invented a new and useful Milk-Bottle Cap, of which the following is a specification.

This invention relates to closures for receptacles, and particularly to closures for ordinary glass milk bottles.

The invention has for its object to provide a novel means for closing the open end of a bottle and to facilitate its easy removal therefrom.

The invention also has for its object to provide a bottle closure that may be used any number of times and may easily be cleaned.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings:

Figure 1 is a top view of the closure.

Fig. 2 is a bottom view of the closure.

Fig. 3 is a cross section as it appears when applied to a receptacle.

Fig. 4 is a cross sectional view showing the closure as it is about to be placed on or removed from a receptacle.

Referring more specifically to the drawings, A represents a bottom disk and B a top disk made of any suitable material, preferably metal. The bottom disk is formed of two segments 1 and 2, and the top disk is formed of two segments 3 and 4. C represents a receptacle.

The segment 1 is flat, and has its straight edge bent downwardly to form a flange 6 provided with openings 7 to form a section of a hinge. The segment 2 is also flat, and has its straight edge provided with downwardly curved members 9, each of which is bent to define a substantially rectangular eye, as shown. These members 9 hook into the openings 7 and form a hinge for the lower disk A.

The segment 3 of the disk B has its arcuate edge 11 bent upwardly and outwardly, and its other edge cut to form a recess 12.

This segment 3 may be riveted or otherwise secured to the segment 1 or can be formed integral therewith. The segment 4 has its arcuate edge 13 bent upwardly and outwardly and its other edge continued, to form a tongue 14 to conform with the shape of the recess 12. The tongue 14 is bent upwardly and outwardly to form a finger 14'. The segment 4 may be riveted or otherwise secured to segment 2, or may be formed integral therewith. It will be seen that when these segments are assembled as above described an annular recess 15 is formed into which may be placed a packing ring 16. It will also be noted that the segments 3 and 4 form a dish in which will be caught any foreign matter which may have fallen upon the top and which will retain such matter from entering the bottle when the top is being put in place or removed.

To apply the closure, the member 15 is held and the closure will flex to the position shown in Fig. 4, the relative movement of the parts being limited by the flange 6 engaging the bottom of segment 2. The partly folded closure is inserted into the mouth of the bottle and then flattened so as to cause the packing 16 to be forced against the wall of the mouth and thereby seal the receptacle. The end 14' of the tongue will stick up above the surface of the segments 3 and 4 so it can be easily pulled upwardly to collapse the closure and permit its withdrawal.

When the top is in place, it is yieldingly held not only by the packing ring, but also by the flange 6 within the eye formed by the piece 9, which as will be noted in Fig. 3, is yieldingly bound by the walls of the eye.

What is claimed is:

1. A milk bottle cap, including a disk comprising hingedly connected segmental sections, a segmental plate secured on one of the segmental sections and having its arcuate edge bent upwardly and defining, with the arcuate edge of the segmental section, a groove, and a tongue extending from the other edge of the segmental plate, a segmental plate secured to the other segmental section and having its arcuate edge bent upwardly and defining, with the arcuate edge of the segmental section, a groove, the said plate having a recess for the reception of the tongue, and a packing ring seated in the groove.

2. A milk bottle cap, including a disk

comprising hingedly connected segmental sections of unequal areas, a dished disk comprising sections secured to the segmental sections, the upwardly extending periphery 5 of the dished disk defining with the periphery of the first disk a groove, and a packing ring seated in the groove.

In testimony that I claim the foregoing as my own, I have hereto affixed my signature in the presence of two witnesses.

FLOYD LANE.

Witnesses:

GEORGE J. GRIGGS,

CLARENCE E. CULVER.
